(57) **CLAIM**

The ornamental design for a blood sampling device, as shown and described.

DESCRIPTION

FIG. 1 is a front, perspective view of the design of the blood sampling device without the sample tube installed.

FIG. 2 is a rear, perspective view of the design of the blood sampling device without a sample tube installed.

FIG. 3 is a right-side view of the design of the blood sampling device without a sample tube installed.

FIG. 4 is a left-side view of the design of the blood sampling device without a sample tube installed.

FIG. 5 is a top view of the design of the blood sampling device without a sample tube installed.

FIG. 6 is a bottom view of the design of the blood sampling device without a sample tube installed.

FIG. 7 is a rear view of the design of the blood sampling device without a sample tube installed.

FIG. 8 is a front view of the design of the blood sampling device without a sample tube installed.

FIG. 9 is a front, perspective view of the design of the blood sampling device in which a sample tube is installed.

FIG. 10 is a rear, perspective view of the design of the blood sampling device in which a sample tube is installed.

FIG. 11 is a right-side view of the design of the blood sampling device in which a sample tube is installed.

FIG. 12 is a left-side view of the design of the blood sampling device in which a sample tube is installed.

FIG. 13 is a top view of the design of the blood sampling device in which a sample tube is installed.

FIG. 14 is a rear, perspective view of the design of the blood sampling device in which a sample tube is installed.

FIG. 15 is a rear view of the design of the blood sampling device in which a sample tube is installed.

FIG. 16 is a front view of the design of the blood sampling device in which a sample tube is installed.

FIG. 17 is a front, perspective view of the design of the blood sampling device in which a sample tube is installed and a latch raised.

FIG. 18 is a rear, perspective view of the design of the blood sampling device in which a sample tube is installed and a latch raised.

(Continued)

FIG. 19 is a right-side view of the design of the blood sampling device in which a sample tube is installed and a latch raised.

FIG. 20 is a left-side view of the design of the blood sampling device in which a sample tube is installed and a latch raised.

FIG. 21 is a top view of the design of the blood sampling device in which a sample tube is installed and a latch raised.

FIG. 22 is a rear, perspective view of the design of the blood sampling device in which a sample tube is installed and a latch raised.

FIG. 23 is a rear view of the design of the blood sampling device in which a sample tube is installed and a latch raised; and,

FIG. 24 is a front view of the design of the blood sampling device in which a sample tube is installed and a latch raised.
